UNITED STATES PATENT OFFICE.

LUTHER D. FULTON, OF TITUSVILLE, PENNSYLVANIA, ASSIGNOR TO THE DE LAVAL SEPARATOR COMPANY, A CORPORATION OF NEW JERSEY.

REFINING OIL.

Application filed July 20, 1922. Serial No. 576,211.

To all whom it may concern:

Be it known that I, LUTHER D. FULTON, a citizen of the United States, residing at Titusville, in the county of Crawford, State 5 of Pennsylvania, have invented certain new and useful Improvements in Refining Oil; and I do hereby declare the following to be a full, clear, and exact description of the invention, such as will enable others skilled 10 in the art to which it appertains to make and use the same.

This invention relates to improvements in the refining of oil and more particularly to an improved method and apparatus for 15 separating wax from mineral oil.

According to the present invention, the oil, containing the wax in solution, is subjected to gradual and progressive cooling by circulating a body of the oil downwardly in 20 a large tank or tower and bringing it first into heat interchanging relation with the cold oil from which the wax has been separated and then into indirect contact with a cooling or refrigerating agent at a lower 25 temperature, and finally the wax is separated from the oil by centrifugal force. The cold oil from which the wax has been separated is then returned for preliminary cooling 30 the oil flowing downwardly through the tank or tower.

The circulation of the warm oil in heat interchanging relation with the cold oil in the top of the tank or tower is a counter-current circulation so that the warm oil is 35 progressively cooled and the cold oil progressively warmed. The circulation of the oil in heat interchanging relation with the cooling or refrigerating fluid in the lower part of the tank or tower is also a counter-current circulation, so that the oil entering 40 the top of the tank or tower as warm oil, and which is preliminarily cooled by heat interchange with the cold oil from the centrifugal separator, is further gradually cooled 45 by counter-current heat interchange with the cooling or refrigerating fluid.

The body of the oil in the tank or tower is thus gradually and progressively cooled during its downward flow, and sudden chilling or "sharp freezing" of the oil is prevented. This slow and gradual cooling of 50 the oil is particularly advantageous in permitting the wax to separate from the oil in a form well adapted for subsequent removal 55 in a centrifugal separator.

The invention will be further described in connection with accompanying drawing illustrating one embodiment of the apparatus of the invention adapted for the practice of the process of the invention. The 60 figure shown in the drawing is in part a vertical sectional view and in part an elevation, with parts shown more or less conventionally for purposes of illustration.

In the apparatus illustrated in the drawing a large container 10 is provided in the form of a vertical tank or tower, which may be made of metal and which is provided with an outer covering 11 of insulating material and enclosed within an outer casing 12 65 of brick or similar material.

Located within the tank or tower 10 are upper and lower coils 13 and 14 respectively. Each of these coils is made up of several horizontal layers, and each layer is made up 70 of a series of pipes extending back and forth, so that a series of pipes (eight in the apparatus shown) are arranged at each layer, and these pipes are uniformly distributed over the horizontal cross-section of the tower. A 75 part of the layers of pipe are arranged with the pipes at right angles to the pipes of other layers, as illustrated. This arrangement insures that the oil flowing down through the tank or tower is brought into 80 intimate contact with the coils so that effective heat exchange will take place.

The coil 13 has an inlet 15 leading from the centrifugal separator for introducing the cold oil from the separator into the coil. 90 The oil passing out at 16 goes to any suitable storage.

The lower coil 14 has its inlet 18 communicating with a suitable source of supply of a cooling medium, such as cold brine or 95 ammonia. The outlet 19 from the coil may return to the refrigerating system from which the refrigerating fluid is supplied.

The tower is provided with an inlet 20 for the oil to be cooled. A distributing plate 100 or perforated baffle 21 serves to distribute the oil evenly in the top of the tower. The tower is intended to be kept full of oil to approximately the level of the distributing plate. An overflow pipe 23 is provided to prevent the oil level from rising too high and a sight-glass 24 is provided for indicating the oil level. Provision is also made for automatically controlling the oil level and the amount of oil entering the apparatus. 105 110

For example, in the apparatus illustrated, a float 25 is provided, carried by the rocker arm 26 and the latter has suitable communication 27 with a pump governor or balanced valve 28, shown conventionally, which controls the supply of oil pumped into the tank. Float controlled automatic regulating devices of this kind are well known and for this reason the specific construction has not 10 been illustrated.

At the bottom of the tower 10 is the outlet 22 from which the cold oil flows through the pipe 33 to the centrifugal separator 34. This separator may be of known construction 15 and may operate either with or without a carrier liquid for assisting in the centrifugal separation of the wax from the oil. From the centrifugal separator the oil, freed from wax, is pumped back to the coil 13 through pipe 15 by the pump 35.

At the bottom of the tower is an agitator 29 driven by gears 31 and the drive shaft 30. This agitator can be operated more or less slowly to prevent the wax from settling out 25 on the bottom of the tower, but in practice, if the operation is properly regulated, I have found that such agitation is not necessary, and when used, only a relatively small amount of agitation is required, and the agitation 30 should not be such as will agitate any considerable amount of the body of oil in the tower.

In the operation of the apparatus, the charging stock or oil from which the wax 35 is to be separated is introduced at the top of the tower through the pipe 20 and is spread out more or less uniformly by the distributing plate 21. This warm oil flows slowly down through the tower where it comes in 40 contact first with the cooling coil 13 and where the temperature is slowly and progressively lowered by the counter-current heat exchange with the cold oil flowing upwardly through the coil. The precooled oil then flows down in heat interchanging 45 relation with the refrigerating coil 14 and comes in contact first with the warmer part of this coil and finally with the coldest part at the bottom. A gradual and progressive 50 cooling of the entire body of oil thus takes place and the wax is in this way separated from the oil in a manner which enables it to be readily recovered from the oil by centrifugal force. It will be seen that the body 55 of oil slowly moving downwardly through the tower is maintained in a quiescent state without any rapid agitation and with only slow downward movement and gradual and progressive slow cooling to permit the desired crystallization or precipitation of wax 60 from the oil. This gradual and progressive cooling of the oil without a marked difference of temperature between the oil and the cooling medium at any point in the tower is particularly important and the construction 65

of this apparatus is such that it is attained to a marked degree. The oil flowing from the separator into the cooling coil 13 is at an intermediate temperature but little below the temperature of the oil in the tower at 70 that point, and its temperature is raised as it flows upward through the coil 13. Also, the brine or other cooling medium in coil 14 is raised in temperature as it flows upward so that at the outlet of the coil 14 its 75 temperature is only a little below that of the oil at the inlet of coil 13. The oil which has thus been prepared for centrifugal separation of wax therefrom is then conveyed to the centrifugal separator, in 80 which the wax is separated by centrifugal force, and the cold oil is then returned for use in the preliminary cooling of the warm entering oil.

The downward flow of the oil in the tower, 85 and the supply of warm oil at the top, results in keeping the oil at the top of the tower warm so that trouble from moisture or particles of ice is eliminated. The downward flow of the oil also assists in preventing 90 settling out of the wax at the bottom of the tower. The oil and wax are of nearly the same specific gravity so that by properly regulating the rate of flow of the oil and the rate at which its temperature is lowered, it is possible to secure a balance in 95 conditions such that the precipitating wax does not settle out of the oil at the bottom of the tower, but is carried along and discharged with the oil. The relative rates of 100 flow and of cooling necessary to produce this condition will, to a large extent, depend on the dimensions of the tower, the area of the cooling surfaces, etc., but may be readily determined in the actual operation 105 of the tower. I have also found that with gradual downflow of oil through the tower and with progressive cooling and separation of wax without any sudden or sharp change in temperature, the wax comes out of 110 solution in a condition well adapted for 115 centrifugal separation.

The oil which is to be treated according to the present invention may vary in character, both in the nature and amount of wax to be separated, and in the character of the oil from which the wax is to be removed. The wax-containing oil may, for example, be one which has naphtha admixed therewith to facilitate the wax separation.

While I have illustrated only one embodiment of the invention, and described it in connection therewith, yet it will be understood that various changes and modifications can be made therein without departing from the spirit and scope of the invention.

I claim:

The method of separating wax from mineral oils containing the same in solution, which 130

comprises slowly flowing a large volume of oil along a downward path without agitation and without substantial change of direction, the oil being maintained in a stream 5 of large cross-sectional area as compared with the length of its path of travel, subjecting the flowing oil to gradual and progressive cooling by indirect contact with a cooling medium, passing upwardly counter-current to the flowing oil, and subjecting the oil so cooled to centrifugal separation.

2. The method of separating wax from mineral oils containing the same in solution, which comprises slowly flowing a large volume 15 of oil along a downward path without agitation and without substantial change of direction, the oil being maintained in a stream of large cross-sectional area as compared with the length of its path of travel, subjecting the flowing oil to gradual and progressive cooling by indirect contact with a cooling medium flowing upwardly counter-current to the down-flow of oil, maintaining such a relation between the velocity 20 of the oil and the rate of cooling that the settling of the precipitated wax from the oil is substantially prevented, and subjecting the cold oil to centrifugal separation.

3. The method of separating wax from mineral oils containing the same in solution, which comprises slowly flowing a large volume 30 of oil along a downward path without agitation and without substantial change of direction, the oil being maintained in a stream of large cross-sectional area as compared with the length of its path of travel, subjecting the flowing oil to gradual and progressive cooling by indirect contact with treated oil and then with a cooling medium 35 at a low temperature, the treated oil and cooling medium flowing upwardly counter-current to the down-flow of untreated oil, and subjecting the resulting cold oil to centrifugal separation, the cold oil after the 40 centrifugal separation of the wax therefrom, being that used for preliminarily cooling the untreated oil.

4. Apparatus for the separation of wax from mineral oils comprising the combination 45 of a large container adapted to permit the flow of a large body of untreated oil therethrough, without substantial change of direction and without substantial agitation, an inlet for the oil at the top of the contain-

er and an outlet for the oil at the bottom of 55 the container, a centrifugal separator for receiving the oil from the bottom of the container, means for circulating the cold oil from the centrifugal separator into heat interchanging relation with the moving body 60 of untreated oil in the upper part of the container, and means for circulating a refrigerating agent in heat interchanging relation with the moving body of oil in the lower part of the container whereby the moving 65 body of untreated oil passing through the container is progressively cooled, first by heat interchange with cold treated oil and later with the refrigerating agent.

5. Apparatus for the separation of wax 70 from mineral oils which comprises the combination of a large container adapted to permit the flow therethrough of a large body of untreated oil without substantial agitation and without substantial 75 change in direction, and having an inlet at the top and an outlet at the bottom, a centrifugal separator for receiving the oil from the bottom of the container, a coil arranged in the upper part of the container, means for circulating the cold treated oil from the centrifugal separator through said coil in a generally upward direction, and another coil arranged in the container below the first coil and adapted for the circulation 80 therethrough of a refrigerating agent in a generally upward direction, both said coils being arranged to provide an extended cooling surface distributed throughout the moving body of oil whereby the temperature of 90 the latter is gradually and progressively lowered.

6. An apparatus for the separation of wax from mineral oils comprising a 95 large container adapted to contain a large body of oil and having an inlet at the top and an outlet at the bottom, means for distributing the oil entering at the top of the container, means for maintaining the level of oil in said container, cooling means in 100 said container adapted for the circulation upwardly therethrough of a cooling fluid, and a centrifugal separator arranged to receive the cold oil from the bottom of said container, and to separate the wax therefrom.

In testimony whereof I affix my signature.
LUTHER D. FULTON.
